UNITED STATES PATENT OFFICE.

CHARLES C. DRAKE, OF TRENTON, NEW JERSEY.

DISTRICT POLICE AND FIRE TELEGRAPH.

SPECIFICATION forming part of Letters Patent No. 430,992, dated June 24, 1890.

Application filed November 4, 1889. Serial No. 329,250. (No model.)

To all whom it may concern:

Be it known that I, CHARLES C. DRAKE, of the city of Trenton, county of Mercer, and State of New Jersey, have invented an Improvement in District Police or Fire Telegraph, of which the following is a specification.

My invention relates to a call-box in which the particular box is indicated by pulsations sent over the line by an automatic circuit-closer and denoting the number or letter of the box in connection with circuit-connections, and a finger-key and bell, by which a message can be sent and an answer received at the call-box while the automatic circuit-closer is held in a fixed position, and when the same is relieved it indicates at the central station the letter or number of the call-box.

At the central station I employ a strip of paper and ink markers or embossers and a magnet brought into action by the incoming current and a clock, by means of which the time is marked upon the paper automatically and periodically, thereby indicating unerringly the time when the call comes in and automatically testing the main line. This is of great importance, as it defines the time when an alarm of fire may be turned in or when an ambulance or police report or call may reach the central station and the testing of the main line.

In the drawings, Figure 1 is a general diagram indicating the circuit-connections, which normally is an open circuit. This is of great importance, as it requires less to maintain the main battery than a closed circuit. Fig. 2 is a section of the call-box with the automatic circuit devices uncovered.

Fig. 1 represents an open circuit; C B, the call-box; B, the main-line battery; C, the clock of the central station; K, the key; R, the inking or embossing register at the central station, all of which are of ordinary construction. It is to be understood that when a signal is turned in from any distant call-box the pulsations from the main battery pass over the line L B—that is, from the ground G², through the call-box C B, to line L B, to register R, through the helix of magnet W, to wire H, to main battery B, to wire G, to ground G'.

I will now describe the balance of the cir-

cuit and connections of key K and clock C. The key K is for the purpose of sending or answering the signals from call-box C B or 55 any number of boxes. The pulsations of the key K pass over the line L R, to call-box C B, through the call-box C B, to line L B, to register R, through the helix of the magnet W, to wire H, to main battery B, to wire G, to junction-wire N, to wire P, to key K, and by so doing it will ring the bell in the call-box C B or in all boxes at the same time. The clock C is so arranged that the pulsations of the clock C will pass over the wire U, to junction-wire 60 I, to line L R, to call-box C B, through the call-box C B, to line L B, to register R, through the helix of magnet W, to wire H, to main battery B, to wire G, to junction-wire N, to wire P, to junction-wire E, to wire M, to circuit- 65 closer in clock C, to wire U, the place of beginning, thereby closing the main line and energizing the magnet W, causing the register R to record the time and at the same time proving the main-line circuit to be in 70 working order. At the call-box C B, Fig. 2, the line L B passes in by the wire L B, to the binding-post 21, to wire 22, to magnet F of call-bell T, through the helix of magnet F, to wire 23, to junction-wire 24, to wire 25, to 75 binding-post 26, and out by line L R, and so on through as many call-boxes as there are in circuit. The call-box thus far named is well known, and I remark that the signal-wheel 27 is raised to send in a certain known 80 number or signal through the circuit-closer 36, to wire 37, to junction-wire 39, to wire 25, to junction-wire 24, to wire 23, to magnet F, through the helix of magnet F, to wire 22, to binding-post 21, to line L B, and from circuit-closer 36 to wire 38, to junction-wire 34, to wire 35, to ground G². The handle 28 is to be turned to bring into position the wheel 27 and to wind up the spring that moves the signal-wheel, and I remark that the pin A 85 is so arranged that while the handle 28 is being turned to bring into position the signal-wheel 27 the pin A has no action upon the lower prong of circuit-closer 36; but when the handle 28 is let go, the pin A becomes rigid, upon coming in contact the raised teeth of wheel 27 closes the circuit-closer 36. This is also usual; but I put upon the signal-wheel 27 the raised tooth 29, so

that when the handle 28 is turned to bring the signal-wheel into position ready for action the raised tooth 29 presses against the spring or circuit-closer 30 and closes the circuit-closer 30. At this time the key S in the signal-box C B can be operated to send in Morse or other characters to the central station and call for assistance, an ambulance, reinforcements, or any other pre-arranged or needed call. In this instance the current passes from the line L B to the binding-post 21, by wire 22 to magnet F of call-bell T, through the helix of magnet F to wire 23, to junction-wire 24, to wire 31, to key S, and when key S is closed to wire 32, to circuit-closer 30, to wire 33, to junction of wires 34, to wire 35, to ground G², and the magnet F and the call-bell T being in the circuit of the key S the sender is able to know whether or not the signals are being sent and an answer can be sent by the key K at the central station and received on the bell T. As soon as the handle 28 is released the mechanism turns the signal-wheel 27 and denotes the number of the call-box to the central station. By this arrangement communication both ways

is provided for; but a message can only be sent by the key S while the handle 28 is held down and the number of the call-box is sent in when the handle is released, thus preventing the possibility of oversight under the most perplexing circumstances. 30

I claim as my invention—

The combination, in a signal call-box, of a signal-wheel and its actuating mechanism 35 with a circuit-closer 30, raised tooth 29, acting upon the circuit-closer 30 and receiving its motion from the handle of the signal-wheel, and a key S in the open circuit 31 24 23, the helix of magnet F, 32, 33, 34, and 35, 40 substantially as set forth, whereby the key S can be operated by hand to signal the central station while the handle 28 is drawn down and the circuit-closer closed at 30, substantially as set forth. 45

Signed by me this 1st day of November, A. D. 1889.

CHARLES C. DRAKE.
